UNITED STATES PATENT OFFICE.

ALBERT HOSSFELD, OF LEWISTON, MINNESOTA.

IRON BENDER.

Application filed July 19, 1922. Serial No. 575,998.

To all whom it may concern:

Be it known that I, ALBERT HOSSFELD, a citizen of the United States, residing at Lewiston, in the county of Winona and State 5 of Minnesota, have invented certain new and useful Improvements in Iron Benders; and I do hereby declare the following to be a full, clear, and exact description of the invention, such as will enable others skilled in 10 the art to which it appertains to make and use the same.

This invention relates to a bending machine and particularly to such a machine adapted to be operated by hand and employed in blacksmith shops, garages, etc. 15 The machine is designed to bend flat bars into various shapes, to bend round stock into eyes, to bend pipe, tubing, etc.

It is an object of this invention to provide 20 such a machine comprising a main frame and a bending frame formed of spaced bars which frames are pivoted together and the main frame being adapted to be attached to a work bench, a post, or held in a vise.

It is a further object of this invention to provide said main frame with a stop block 25 suitably supported and eccentrically mounted to present various surfaces in operative position.

It is still another object of this invention to equip the bending frame with an adjustable device for forming eyes.

It is also an object of this invention to provide the main frame with simple and efficient gauging means.

These and other objects and advantages of the invention will be fully set forth in the following description made in connection with the accompanying drawings in which 40 like reference characters refer to the same parts throughout the different views and, in which,

Figure 1 is a view in side elevation of the machine;

Fig. 2 is a view showing a central horizontal section through the device;

Fig. 3 is a vertical section taken on line 3-3 of Fig. 1, as indicated by the arrow;

Fig. 4 is a top plan view of the device;

Fig. 5 is a horizontal section taken substantially on line 5-5 of Fig. 1;

Fig. 6 is a view partly in plane and partly in horizontal section of the device;

Fig. 7 is a view in elevation illustrating 55 certain parts of the device; and

Fig. 8 is a partial plan view illustrating one operation of the device.

Referring to the drawings,

The device is seen to comprise a main frame formed of spaced flat bars 1 having a 60 spacing collar 2 therebetween secured to the bars 1 by a headed and nutted bolt passing through said collar and bars. The bars 1 converge at one end and have spacing members 3 riveted thereto and are adapted to be 65 attached to a working bench or post A by bolts 4^a extending therethrough and between said bars. The outer ends of the bars 1 are apertured to receive a pivot pin 4 forming 70 the connecting means for a bending frame formed of bars 5 spaced at one end to fit between the bars 1 and which converge at their other end where they are riveted to a handle member 6. The lower bar 1 has bolted there- 75 to beneath the same, by spaced bolts 7 and 8, a bar 9 which is spaced therefrom. A small flat bar 10 having a hub pivoted on bolt 8 and disposed between members 9 and 1 is supported on the former and in turn forms the supporting means for the pin 4. The 80 bar 9 is provided with an aperture 11 in alinement with the pin 4 to which said pin is adapted to pass at certain times.

The bars 1 are provided with a pair of 85 spaced aligned holes 12 adapted to receive a pin member 13, the lower end of which rests upon the bar 9 and the upper end of which is reversely bent to extend parallel to the main portion thereof. This latter bent end is spaced from the main portion a distance 90 equal to the spacing of the holes 12 so that said end can enter the hole adjacent to the one occupied by the main portion of the pin. The bent portion of this pin is adapted to receive a collar or roll member 14 which is 95 rotatable thereon and which is held in position slightly above the top bar 1 by a pin 15 projecting from one side of said bend. The main portion of the pin 13 extending between the bars 1 is adapted to pass through 100 a longitudinal aperture formed in a stop block member 16, the said aperture being located at different distances from the plane surfaces forming the sides of said block. A member 17 having its end bent around the bolt 7, and held thereon by the nut and washer on said bolt, extends along the top 105 of the lower bar 1 and forms a support for the block 16. A guage member 18 formed of a small round rod is provided and formed 110

substantially as a circle concentric with the pin 4, the end of said member being formed with eyes through which passes the bolt 7, said eyes being disposed between the bar 9 and the lower bar 1. One or more sliding gauge members 19, in the form of clips, frictionally engage the member 18 for sliding movement thereon. Another gauge member 20 has an eye at one end secured on the bolt 8 and this member also carries a clip 21 frictionally slidable thereon.

The bars 5 are likewise provided with a plurality of spaced aligned holes 22 adapted to receive a pin member 23 similar to the pin 13. The pin member 23 as well as the pin 4 are adapted to receive rolls 24 and 25 of various diameters, which rolls will be rotatable on said pins.

A bending blade or member 26 extends in a vertical plane between the bars 5 and has a shank member secured thereto having a socket at its rear end. This member and socket are adapted to be engaged by the rounded end of a rod 27 which is threaded adjacent said rounded end and extends through a nut 28 abutting against the inner portion of the hollow handle member 6 through which the rod 27 extends. Said rod 27 is formed with a transverse handle member at its outer end and is held in suitable position in said handle member 6 by pins extending transversely through said handle. A coil tension spring 28^a is connected at one end to one of the rivets passing through handle 6 and at its other end to an eyelet secured in the shank of member 26 and is adapted to retract the latter member toward the handle 6 when such movement is permitted by the rod 27.

A member 29 having a U-shaped portion is adapted to be attached to the top of bars 5 by suitable headed and nutted bolts passing through the holes 22 and this member is provided at its front edge with a bevelled or sharpened edge as is also the member 26. The pin 4 projects upwardly above the upper bar 1 and is adapted to co-operate with the member 29 in the bending operation either with or without a bending roller thereon.

The rollers on the pin 4 can be replaced with appropriate bending dies such as the pipe bending die 30 and the pins 13 and 23 may then be provided with appropriate grooved rollers such as shown at 31 in Figs. 6 and 7.

Flat bars may be bent in the machine by placing the same against one side of the block 16 as shown by the piece of work B in Fig. 2. Such bars may be bent about the pin 4 or the roller thereon by rollers carried by pin 23, the bending roller and the stop block being adjusted in the proper holes in the bars 1 and 5 to give the desired bend.

The ends of the flat stock can be bent to

form eyelets by means of the blade member 26. Such bending may be done by giving the bending frame 5 small increments of turning movement and moving the member 26 progressively inward after each of such movements by turning the rod 27. The stock is thus bent closely about the bending pin or roller. When the rod 27 is progressed toward pin 4, the nut 28 will bear against the end of handle 6 and the rod will progress through and push the member 26 inwardly. Said member will be held in position by the pin 23 passing between the member 26 and the projection 26^a on the shank thereof.

Eyelets on smaller stock can be bent by placing the stock C against the roller 14 and bending the same about the upper portion of pin 4 by member 29 as illustrated in Fig. 4. These eyelets as well as those bent by the member 26 can be centered on their shanks by turning the same over after the initial bending and further bending the same as illustrated in Fig. 8. Eyelets formed on the top of pin 4 can, of course, be raised from the top of said pin. After an eyelet is formed by the members 5 the same can be removed by moving member 10 to uncover the aperture 11 and then tapping the top of pin 4 to cause the same to drop through the said aperture and thus release the bent work. The desired angle of bend can be indicated and the amount of bend of the work gauged by the clips 19 which may be adjusted at various points about the member 8. If it is desired to bend a number of pieces alike, the gauge rod 20 and the clip 21 may be used to indicate the distance of the bend from the end of the stock as illustrated in Fig. 4.

The operation of bending piping or tubing D is illustrated in Fig. 6 and it is thought that the same will be clear without further description.

From the above description, it is seen that applicant has provided an extremely simple and efficient bending machine and one which may be found of great service in small shops. The parts of the device are made from very common and standard material and can be made very strong and rugged. The machine can easily be attached to a post or other convenient place in the shop and the machine, though operated by hand, is capable of bending flat stock $\frac{3}{8}$ of an inch in thickness by 3 inches wide, said stock being bent cold. The capacity of the machine, of course, will be greatly increased in bending hot stock. The utility of the device has been demonstrated in actual practice and the device has been found invaluable for bending angles, rounded or square, and flat stock as well as piping and tubing, and for making links, eyelets, hooks, etc.

It will, of course, be understood that various changes may be made in the form, de-

tails and arrangement of the parts without departing from the scope of applicant's invention, which, generally stated, consists in the matter shown and described and set forth in the appended claims.

What is claimed is:

1. A bending machine comprising a main frame formed of spaced horizontal bars converging at one end and adapted to be attached to a support, a bending frame also comprising spaced horizontal bars converging at one end and carrying a hollow handle member, a roller-carrying bending pin pivotally connecting the bars of said frames at one end thereof, a work-contacting and bending member movable between the bars of said bending frame, and means extending through said handle member for contacting and moving said work-contacting member toward and holding the same to the work, said means being provided with an operating handle beyond the end of said hollow handle member.

2. The structure set forth in claim 1, and automatically acting means for moving said work contacting member away from said bending pin and work.

3. A bending machine comprising a main frame, a bending frame comprising spaced horizontal bars, said bars converging at their outer ends and carrying a hollow handle, a roller-carrying bending pin pivotally connecting the inner ends of said bars to said main frame, a work bending member movable longitudinally between the bars of said bending frame, a nut abutting said handle, a screw extending through said handle engaging said nut and contacting said work bending member to move said member inwardly, and a spring secured to said member and handle to retract said member.

4. A bending machine having in combination, a main frame comprising spaced horizontal bars, a bending frame comprising spaced horizontal bars pivoted to the bars of said main frame by a vertical pivot pin, a work bending member movable longitudinally between the bars of said bending frame toward and from said pivot pin and adapted to bend work thereabout, said pin extending above said main frame, and a longitudinally adjustable work bending member mounted on the top bar of said bending frame adapted to move therewith and bend work thereabout said portion of said pin extending above the main frame.

5. A bending machine having in combination, a main frame, a bending frame comprising vertically spaced members pivoted thereto by a vertical pivot pin, a work-con-

tacting member having a vertical edge parallel to the axis of said pin supported between the bars of the bending frame and movable toward and from said pin, means for guiding said work-contacting member longitudinally, a hollow handle carried by and extending from said bending frame, means carried by and extending through said handle for moving said work-contacting member inwardly and holding the same to the work and automatically acting means for moving said work-contacting member outwardly.

6. A bending machine having in combination, a main frame comprising spaced horizontal bars adapted to be attached to a support, a bending frame also comprising spaced horizontal bars, a vertical pivot pin connecting the inner ends of the bars of said frames, the bars of said main frame having series of alined holes therethrough, a pin insertable in any pair of said alined holes, an angular stop block eccentrically mounted on said pin, and means for supporting said block above the lower bar of said main frame.

7. A bending machine having in combination, a main frame comprising vertically spaced bars, a bending frame swingable relatively thereto, a member passing through the bars of said main frame, a stop block held between said bars by said member, the upper end of said member being bent into parallel relationship with the main portion thereof and a work contacting member on the bending frame for bending work about said pivot pin.

8. A bending machine having in combination, a main frame comprising vertically spaced members, a bending frame comprising vertically spaced members, a pivot pin connecting the ends of said frames forming a bending pin about which the work is bent, a member secured to the main frame beneath and spaced from the same and swinging means on said member for supporting said pin, said member having an opening therethrough in alignment with said pin whereby said means can be swung to permit the pin to pass through said opening.

9. A bending machine having in combination, a main frame, a bending frame, a pivot pin connecting the ends of said frames and forming a bending member about which the work is bent, work engaging means on said bending frame for bending work about said pin and movable means for supporting said pin which can be moved to permit said pin to drop.

In testimony whereof I affix my signature.

ALBERT HOSSFELD.
